DESIGN.

H. BECKER.

SEAMSTRESS SEWING CABINET,
APPLICATION FILED OCT. 24, 1916.

50,214.

Patented Jan. 23, 1917.

Inventor

Henry Becker.

By his Attorney

Oscar Geier

UNITED STATES PATENT OFFICE.

HENRY BECKER, OF NEW YORK, N. Y.

DESIGN FOR A SEAMSTRESS SEWING-CABINET.

50,214.

Specification for Design.

Patented Jan. 23, 1917.

Application filed October 24, 1916. Serial No. 127,506. Term of patent 7 years.

To all whom it may concern:

Be it known that I, HENRY BECKER, a subject of the Emperor of Germany, residing at New York, in the county of New York and State of New York, have invented a new, original, and ornamental Design for a Seamstress Sewing-Cabinet, of which the following is a specification, reference being had to the accompanying drawing, forming part thereof.

The figure is a perspective view of a seamstress sewing cabinet showing my new design.

I claim:—

The ornamental design for a seamstress sewing cabinet as shown.

HENRY BECKER.

Witnesses:

WARREN E. WILLIS,
LULU A. KOHLMANN.
